UNITED STATES PATENT OFFICE.

RICHARD RABY, OF LOUDONVILLE, OHIO, ASSIGNOR OF ONE-HALF TO GEORGE F. RABY, OF LOUDONVILLE, OHIO.

IRONING-BOARD.

1,359,744.

Specification of Letters Patent. Patented Nov. 23, 1920.

Application filed January 20, 1920. Serial No. 352,804.

To all whom it may concern:

Be it known that I, RICHARD RABY, a citizen of the United States, residing at Loudonville, in the county of Ashland and State of Ohio, have invented certain new and useful Improvements in Ironing-Boards, of which the following is a specification, reference being had therein to the accompanying drawing.

- 10 The invention relates to ironing boards and has for its object to provide an ironing board which is supported on a single standard and to provide means whereby one end of the ironing board may be securely clamped to the edge of a table or the like. Also to provide means whereby the end of the ironing board may be clamped between supports located on each side of the ironing board.
- 15 A further object is to provide an ironing board wherein a single standard is used, said standard being provided with an extension leg so that the ironing board may be supported at various heights from the floor. Also to provide a brace for said standard which brace is spring actuated so that when the standard is folded against the bottom of the ironing board said spring actuated brace will maintain the standard in collapsed position.

20 A further object is to provide a clamping member comprising a metallic strip extending transversely of the end of the ironing board, said strip being provided with recesses for the reception of the ends of clamping members, the other ends of said clamping members being downwardly offset and adapted to engage under a supporting table and to provide bolts passing through the end 25 of the ironing board which engage the upper surface of the table and through the clamping members. Also to provide a tailor's goose support comprising a bracket passing through an aperture in the ironing board and provided with a lug adapted to engage a transverse metallic strip on the under surface at the rear end of the ironing board.

25 With the above and other objects in view the invention resides in the combination and arrangement of parts as hereinafter set forth shown in the drawings described and claimed, it being understood that changes in the precise embodiment of the invention may 30 be made within the scope of what is claimed

without departing from the spirit of the invention.

In the drawings:—

Figure 1 is a perspective view of the ironing board.

60

Fig. 2 is a side elevation.

Fig. 3 is a longitudinal sectional view.

Fig. 4 is an enlarged detail view of the clamping end of the ironing board.

Fig. 5 is a detail sectional view through the end of the board and one of the clamping members.

Fig. 6 is a perspective view of the board carried plate of the clamp.

Referring to the drawings, the numeral 1 designates a conventional form of ironing board, to the under face of which is pivoted between brackets 2 as at 3, a downwardly extending supporting leg 4. The lower end of the supporting leg 4 is bifurcated as at 5, and in which bifurcation the arm 6 of the supporting leg 7 is adjustably secured by means of a slot 8 and bolt 9. Bolt 9 and slot 8 allows the leg as a whole to be adjusted for supporting the ironing board at various heights from the floor. The lugs 2 are carried by a transversely disposed plate 10, which plate is secured to the under face of the ironing board and forms means for preventing warping of the same. Leg 4 near

70 its pivotal point 3 is provided with an aperture 11, through which aperture a pin 12 extends. Pivoted on a plate 13 which is secured to the under face of the ironing board is a brace 14. Brace 14 near its free end is 75 provided with a notch 15, which notch engages the pin 12 and prevents the collapse of the leg 4 during an ironing operation. A leaf spring 16 is provided, one end of which leaf spring has a bearing on the plate 13 and 80 passes over a pin 17. The other end of said spring 16 being disposed beneath a lug 18 so that the free end of the pivoted arm 14 is normally held upwardly in engagement with the pin 12. It will be seen that if the leg 4 85 is moved in the direction of the arrow *a* that the spring actuated arm 14 will hold said leg in collapsed position against the bottom of 90 the ironing board.

95 Secured to the ironing board adjacent its rear end is a transversely disposed metallic strip 19 which strip forms a batten for preventing warping of the ironing board. Metallic strip 19 at its rear edge adjacent each 100 side of the ironing board is provided with 110

struck down depressions, which depressions are struck down to such an extent that the arms 20 of clamping members 21 will pass over the struck down portions 22 and beyond said portions 22 so that their ends 23 will engage under the plate 19. Members 21 are provided with downwardly extending offset portions 24, which portions adjacent their ends are provided with transversely disposed ribs 25 adapted to engage the under face of a supporting table 26. Ribs 25 are spaced inwardly of the end 27 of the ironing board so that said end will in conjunction with the clamping members 21 form a clamp between which clamp the edge of the table 26 is clamped. Passing through the ironing board and also through the clamping members 21 are vertically disposed bolts 28, the lower ends of which bolts are provided with butterfly nuts 29 by means of which the clamping members 21 and the ironing board may be securely clamped on a table. Clamping members 21 however are provided with outwardly extending lugs 30, which lugs may be utilized for clamping the end of the board to spaced members, one of which is located on each side of the ironing board.

A small board 31 is disposed above the ironing board 1 and is supported on a bracket 31^a. The lower end of the bracket 31^a when in supported position is passed through an aperture 32 in the ironing board and has its right angle portion 33 in engagement with the metallic strip 19 thereby preventing strain upon the board and placing the strain on the metallic member 19 which is located at the most stable part of the board. Bracket 31^a is provided with horizontally disposed flanges 34 which engage the upper face of the ironing board and prevent the marring and breaking of the same during an ironing operation on the small board 31.

From the above it will be seen that an ironing board is provided which is supported by a single adjustable leg and one wherein the use of a great number of bolts is obviated. It will also be seen that the

clamping members 21 only require two bolts 50 and that their clamping action will be positive. By providing the lug 33 on the bracket 31 it will be seen that during an ironing operation that the strain will be thrown on the metallic member 19 adjacent the rigid supporting point of the main ironing board, thereby obviating wobbling and at the same time eliminating securing means for the bracket 31 which would have to be unfastened or loosened to remove the small board, 60 it only being necessary when it is desired to remove the small board to raise the bracket 31^a out of the aperture 32.

The invention having been set forth what is claimed as new and useful is:—

The combination with an ironing board, of a supporting leg therefor, said leg being pivoted to the underside of the board and provided with an elongated aperture adjacent its pivotal point, an extension 70 member carried by said leg, a spring actuated arm pivoted to the under side of the ironing board and having its free end disposed in the aperture of the leg, said free end of the arm being provided with a notch 75 spaced from the end thereof, a pin extending through the pivoted leg and the upper end of the elongated aperture, said pin being received by the notch in the pivoted arm when the supporting leg is in vertical position, the portion of the pivoted arm between the notch and the free end of the arm being of sufficient length to engage the side of the leg when it is folded in the direction of the end of the board for holding said leg 80 against the board in collapsed position, a leaf spring secured to the board adjacent the pivotal point of the arm and to the lever for normally forcing said lever upwardly, the free end of the leaf spring being in engagement with the side of the arm, thereby allowing the supporting leg to be collapsed in the opposite direction and held in collapsed position.

In testimony whereof I hereunto affix my 95 signature.

RICHARD RABY.
